[57] CLAIM

The ornamental designs for a golf club brush, as shown in the figures.

DESCRIPTION

FIG. 1 is a front elevational view thereof;

FIG. 2 is a right side elevational view thereof;

FIG. 3 is a left side elevational view. The club can be a right hand or left hand club and therefore FIGS. 2 and 3 will alternate from a right or left hand club;

FIG. 4 is a rear elevational view thereof;

FIG. 5 is a top plan view thereof; and,

FIG. 6 is a bottom plan view thereof.
